LOOM

Joseph L. Baker, Langhorne Manor, Pa.

Application May 21, 1941, Serial No. 394,409

15 Claims.

(Cl. 139—20)

My invention relates to looms and is more particularly intended and adapted to weave pile fabric. A loom embodying my invention embodies new combinations of old features and also features novel per se, all of which cooperate to effect a more rapid production than has heretofore been possible.

It has long been known to utilize, instead of the usual bobbin-carrying shuttle, a shuttle that carries no bobbin and which, instead, after traversing of the warp shed, engages yarn extending from a stationary bobbin at one side of the loom and pulls the same across the loom, to thereby insert a double shot of weft, the shuttle then engaging yarn from a similar bobbin on the opposite side and traversing the warp shed in opposite direction and pulling the yarn across the loom to thereby insert another double shot of weft. Since a shuttle of this character carries substantially no weight of yarn, it may be made of comparatively small size and mass and may be operated more rapidly than the ordinary shuttle. Nor is it necessary to stop the loom at frequent intervals, as in the use of an ordinary shuttle, in order to replenish the yarn supply. The two factors of higher speed of operation and continuous operation result in a considerably increased production over that of the ordinary loom.

Another type of loom that gives increased production is one in which two shuttles of the ordinary type simultaneously travel through warp sheds at different levels to thereby simultaneously weave two fabrics.

In my invention, I combine these two features in one loom, thereby securing the advantages of both types of loom, thereby increasing production to a degree not heretofore obtainable on any type of loom.

To enable these separately old features to be combined in a single loom and weave fabric of the type for which the loom is more particularly intended and adapted, the warp sheds and, more particularly, the shuttles are operated in a peculiar and novel manner. While one shuttle is traveling across the loom at a higher level, the other shuttle is at the same time traveling at a lower level in the opposite direction. After the shuttles complete their traverse, the first shuttle is dropped to the lower level and the second shuttle is raised to the higher level and the shuttles are then again shot across the loom simultaneously in opposite directions. Thus each shuttle travels, first in one direction through the

upper warp shed and then in the opposite direction through the lower warp shed.

The double pile fabric for the manufacture of which the loom is more particularly adapted comprises, besides the described weft or filler yarn pulled through the warp sheds by the shuttles, binder warp yarn which is woven only into the upper fabric, binder warp yarn which is woven only into the lower fabric, and pile warp yarn which is woven into both fabrics. Optionally each fabric also contains a stuffer warp. A typical fabric of this character is hereafter described.

The invention, besides comprising means for effecting the operation of the shuttles in the novel manner above described, comprises also means for inserting a selvedge thread in the loops formed by weft yarn, the operation of the selvedge thread shuttle being controlled partly by mechanism controlled by the lay and partly by mechanism controlled by the weft shuttles.

A preferred embodiment of the invention is shown in the accompanying drawings, in which—

Fig. 1 is a side view of the loom, a few parts being shown in section.

Fig. 2 is a front view of the loom.

Fig. 3 is a plan view of part of the loom.

Fig. 4 is a perspective view of part of the loom.

Fig. 5 is a cross-section through one of the shuttle boxes with an end view of one of the two weft shuttles.

Fig. 6 is a side view of one of the weft shuttles with the selvedge shuttle shown in end view.

Fig. 7 is a detail side view of the selvedge shuttle box and of some of the selvedge shuttle operating mechanism, one of the weft shuttles being shown in cross-section.

Fig. 8 is a detail perspective view of part of the mechanism shown in Fig. 7.

Fig. 9 is a view, similar to Fig. 6, showing also some of the mechanism for controlling from a weft shuttle the selvedge shuttle operating means.

Figs. 10 and 11 are detail views of a part of the last named mechanism.

Fig. 12 is a diagram, along the line of the warp, of a fabric which the loom is adapted to weave.

Fig. 13 is a diagram of the same fabric along the line of the weft.

Figs. 14 and 15 are diagrams showing the weft yarns, the selvedge yarns on opposite sides and the shuttles for operating the several yarns.

Fig. 16 is another side view, similar to Figs. 7, of the mechanism controlling the operation of the selvedge shuttle.

1 is the loom frame; 2 the main driving shaft; 3 the lay; 4 the lay swords, fulcrumed at 5 and

driven from the main shaft by the crank and pitman 6; 7 the reed; 8 the breast beam; and 9 the harness.

A double fabric which the loom is adapted to weave is shown diagrammatically in Figs. 12 and 13. It comprises two identical parallel fabrics, which I shall designate upper and lower fabrics. These fabrics comprise, respectively, binder warps *a*, *b* and *c*, *d*, stuffer warps *e* and *f*, pairs of filler wefts *g*, *g'* and *h*, *h'*, and a pile warp *i* common to both fabrics. 10 and 11 (see Fig. 1) are the upper and lower binder warp beams and 12 and 13 the upper and lower stuffer warp beams. The pile warp beam is not shown. 14 and 15 are spools, bobbins or cones, one on each side, carrying two yarns *G* and *H* which form the filler wefts *g*, *g'* and *h*, *h'*.

The two shuttles 20 and 21, carrying the filler wefts across the loom carry no bobbins. They are actuated in the known manner by picker blocks 220 and 230 operable by picker sticks 22 and 23. Each shuttle, near the beginning of its traverse, engages the filler yarn at one side of the loom, carries the yarn across the loom at a higher level, disengages the yarn, engages the filler yarn at the other side of the loom and carries it in the opposite direction across the loom at a lower level.

The specific operation of the shuttles and the fabric formed thereby will be more clearly understood by reference to Figs. 2 and 3 and the diagrams in Figs. 12 and 13 of the fabric. Referring to Figs. 12 and 13, the filler wefts *g* and *g'* comprise a single yarn *G*, which is fed from one bobbin (say 14), and the filler wefts *h* and *h'* comprise a single yarn *H*, which is fed from the other bobbin 15.

Assume that shuttle 20, in its movement from left to right, has engaged (by means of pin 200 carried thereby) yarn *G* fed from bobbin 14 at the left side of the loom and has pulled the same across the loom at the higher level between sheds formed by binder *a* and stuffer *e* to form the pair of wefts *g* of the upper fabric. Concurrently with the above operation shuttle 21 engages (by means of pin 210) yarn *H* fed from bobbin 15 at the right side of the loom and pulls the same across the loom at the lower level between the sheds formed by binder *c* and pile warp *i* and binder *d* to form the pair of wefts *h* of the lower fabric.

Shuttle 20, which is now at the right side of the loom and dropped to the lower level, engages yarn *H* fed from bobbin 15 at the right side of the loom and is thrown across the loom to the left, and pulls yarn *H* across the loom between the sheds formed by binder *d* and stuffer *f* and binder *c* to form the pair of wefts *h'* of the lower fabric. At the same time shuttle 21, which has been raised to the higher level, engages yarn *G* fed from bobbin 14 at the left side of the loom and is thrown across the loom from left to right between the sheds formed by binder warp *b* and pile warp *i* and binder *a* to form the pair of wefts *g'* of the upper fabric.

Thus two double shots of weft are simultaneously carried across the loom one in each direction, the two shuttles traveling in different horizontal planes. The described operation requires that at the beginning of each such movement the two shuttles shall be in two different horizontal planes and that at the end of each such movement each shuttle shall be moved into the other horizontal plane. Thus, referring to Fig. 75

2, shuttle 20 is in its upper position and shuttle 21 in its lower position. After their simultaneous movement in opposite directions across the loom, shuttle 20, which is now at the right side of the loom, is lowered to the position occupied by shuttle 21 in Figure 2, while shuttle 21, which is now at the left side of the loom, is raised to the position occupied by shuttle 20 in the figure. Thus each shuttle engages and carries one filler yarn *G* in its throw in one direction and the other filler yarn *H* in its throw in the other direction, all the filler yarn *G* being thus in the upper cloth and all the filler yarn *H* in the lower cloth.

The means for raising and lowering the shuttle 15 will now be described. Each shuttle at the end of its travel in the lower plane to the left, Fig. 2 (see also Figs. 1, 3, 4 and 5) is thrown into a shuttle box 25, which has one rigid side wall 26 and one flexible side wall 27, the latter being 20 normally held in parallel relation with the side wall 26 by means of a leaf spring 28. When the shuttle enters box 25, it rests on a lifter 29 (see Figs. 4 and 5), the two arms of which are 25 slideable up and down on the lay 3 (see also Fig. 4). When a shuttle thus traveling in the lower plane enters the shuttle box 25, the lifter is in its lower position, but immediately thereafter is raised to its upper position, as shown in dotted lines, Fig. 5, thereby lifting the shuttle to the 30 upper plane. As the shuttle completes its up movement, it engages a catch 30 on the flexible side wall 27 of the shuttle box and forces the side wall slightly outward. Upon reaching its final 35 up position, the spring 28 snaps the side wall back to its normal position, catch 30 then snapping under the shuttle, which is retained in its up position between the two side walls of the box, resting at one side on catch 30 and on the other side on a projection 300 on the inside of 40 the rigid wall 26.

The lifter is moved into its down position and normally held there by means of a lever 31 pivoted between its ends to arms depending from the lay 3, one end of the lever being attached to the lifter 29, and the other end being normally held up by a tension spring 32. The last named end of lever 31 is connected with one end of a lever 33 by means of a bolt and spring connection 34, shown more clearly in Fig. 4, the other end of lever 33 being pivoted on the loom frame. Just after the shuttle enters box 25, an arm 36 on shaft 2 (see Fig. 1) engages a cam 35 on lever 33 and lowers the end of lever 33 connected with lever 31, thereby lifting the end of lever 31 attached to lifter 29, thereby lifting the shuttle as above described into the upper plane preparatory to its throw to the right. Upon recession of arm 36 from cam 35, levers 33 and 31 are immediately returned by spring 32 to their normal positions, thus lowering lifter 29 into position to receive the other shuttle upon the latter's completion of its throw to the left.

As hereinbefore stated the operation requires that on the right side of the loom the shuttle that has been thrown to the right in the upper plane 65 shall be dropped to the lower plane preparatory to its throw to the left. The shuttle box 40 at the right is similar in construction to shuttle box 25 in that it has one rigid wall 38 and one flexible wall 39 normally held in parallelism with the rigid wall by means of a leaf spring 41. When a shuttle, travelling in the upper plane, enters box 70 40, it sides under and then rests under a depressor 42 having depending arms slideable, like the arms depending from lifter 29, up and down

on the lay 3, the depressor at this time being in the up position. A detail view of the depressor 42 is not necessary, since its construction may be the same as that of lifter 29 except that it need not have the latch 30 or the projection 300 of the lifter. The depressor is normally held in the up position by means of a lever 43 under the tension of a spring 44. Lever 43 has a bolt and spring connection with a lever 45. Just after a shuttle enters box 40, an arm (similar to arm 36) on shaft 2 engages a cam on a lever 45 and lifts it to thereby swing the lever 43 and lower the depressor 42, thereby lowering the shuttle to the position shown in Fig. 2. The picker stick 23 then immediately throws the shuttle to the left, Fig. 2, after which the arm 46 travels beyond the cam on lever 45 and spring 44 immediately swings lever 43 to raise the depressor into position to receive the other shuttle in its throw to the right.

So far as the construction of the loom has been described, it will be understood that the loom and its operation embody the following novel combination of characteristics.

The shuttles do not carry their own bobbins but each merely pulls across the loom a double weft yarn fed from a stationary supply. While such mode of feeding the weft is known in the art, it will be observed that two shuttles of this type move simultaneously in opposite directions, so that two double pairs of weft are simultaneously inserted, but attention is particularly directed to the fact that each shuttle travels in both horizontal planes and cooperates with the other shuttle to form two simultaneously woven fabrics having separate wefts. This operation is effected by causing each shuttle, alternately, to engage the weft thread at one side of the loom and pull a double pick thereof in one direction in one plane through the warp shed of one fabric and then, after releasing such weft thread, causing the shuttle to engage the weft thread at the other side of the loom and pull a double pick thereof in the opposite direction through the warp shed of the other fabric.

The next feature of the invention is the shuttle (hereinafter called the selvedge shuttle, as distinguished from the weft or filler shuttles) and the means for operating it in harmony with the movements of the elements hereinbefore described. The selvedge shuttles, there being one on each side of the loom, are so operated as to lay selvedge yarns through the end loops of the weft, the shuttle traveling parallel with the warp, its movement being effected by mechanism controlled by the lay sword and weft shuttles as hereinbefore described. Each selvedge shuttle is adapted to insert yarn through a loop of weft as the shuttle carrying the looped weft approaches the end of its throw.

The mechanism controlling the operation of the selvedge shuttle 50 is illustrated in Fig. 1 and in Figs. 6-11 and Figs. 14-16, inclusive. Referring more particularly to Figs. 1 and 7, 51, designating the trough or main body of the shuttle box for the selvedge shuttle, is pivotally carried by the lay sword 4 and has a rearward extension which passes through a pivoted support 510 on the frame 1 to maintain the shuttle box in a substantially horizontal position at all times. The shuttle box has a cut-away portion which allows the weft shuttles to travel through it and so position the weft loop as to allow the selvedge shuttle to pass through the loop and carry the selvedge yarn *k* therethrough.

The shuttle 50 is carried by a plate 52, which is slidable longitudinally relative to the trough 51. By reference to Fig. 7 it will be seen that the shuttle is confined between a projection 53 on the plate 52 and the down-turned extremity of the plate. Pivotedly connected at one end with the lay sword is a lever 54 connected at its other end, by means of an adjustable pin and slot connection, with one end of a lever 55, fulcrummed between its ends and pivotally connected at its other end to a sleeve 56. The flat plate 52 has an extension 57, round in cross-section and slidable in the sleeve 56. 58 is a spring secured at one end to the lever 55 and at its other end to a bifurcated lever 59 pivoted to a stud 520 adjustably secured to the plate 52.

After the lay has moved to the extreme right and when it has then moved some distance to the left and has reached the position shown in Fig. 1, the trough 51 and the plate 52 and shuttle 50 are in the relative positions shown in Fig. 7. In this position, the plate 52 is locked to the trough 51 by a spring pressed locking lever 60 pivotally mounted on the trough and engaging a projection 61 on the plate 52 (see Fig. 8); and the spring 58 is under tension. At this point the warp shed is sufficiently open to allow the weft shuttle to pass therethrough. As the weft shuttle moves through the cut-away portion of trough 51, the locking lever 60 is tripped, by mechanism hereinafter described, releasing the plate 52 and allowing the spring 58 to snap the plate quickly to the right, carrying shuttle 50 with it and laying the selvedge yarn *k* within the loop carried by the weft shuttle.

The movement of the plate 52 to the right is arrested by the engagement of stop 570, secured to plate 52, with the end of sleeve 56. During the movement of the lay to the extreme left and during its movement to the right, the trough 51 and plate 52 remain disengaged until, just before the lay completes its swing to the right, the locking lever 60 re-engages the projection 61. In the return movement of the lay and trough 51 to the left, the plate 52, which is now locked to the trough 51, moves to the left, while the upper arm of lever 55 is moving to the right, thereby imposing a considerable tension on spring 58, until, when the trough 51 reaches the position shown in Fig. 1, the spring is under sufficient tension, upon the disengagement of the locking lever 60 with projection 61, to snap the plate 52 and shuttle 50 to the right, as hereinbefore described.

The locking lever 60 is released, as hereinbefore described, by mechanism actuated by the weft shuttles. It has been hereinbefore mentioned that each shuttle carries a pin (200) which engages the weft or filler yarn. This pin is shown in detail in Figs. 7 and 9. It is actually a lever pivoted between its end on the shuttle, the lower end being actuated by a compression spring 62 or equivalent over-center tension spring and being held thereby either in position against one or the other of the stops 63 to hold the pin either in weft-engaging position or in weft-releasing position.

Referring now to Figs. 10 and 11, as well as to Figs. 7 and 9: The pin 200 is pivotally mounted on its weft shuttle by being secured to a shaft 65 turnable in the shuttle. To shaft 65 is also secured a bell crank 66. Turnable in the lay sword 4 is a shaft 67 carrying at one end an arm 68 and at the other end an arm 69 normally held against a stop 70 by a spring 71. When a weft shuttle reaches a given point in its travel, one of

the arms of the bell crank 66 on shaft 65 strikes the arm 68. This engagement snaps the pin 200 from the position shown in Fig. 9 to its other position to release the yarn carried by the pin and also snaps the arm 69 from the position shown on Figs. 8, 10 and 11 to a lower position, in which movement arm 69 depresses the locking lever 60 and thereby unlocks the plate 52; whereupon, as hereinbefore described, spring 58 moves plate 52 rapidly to the right, carrying the shuttle 10 through the loop in the weft yarn.

As the woven double fabric is fed intermittently forward the connecting pile yarn is severed by a cutter 80 (see Fig. 1) and the two pile fabrics are pulled around the spike rolls 81 and 82.

The means for operating the warp yarns to form the warp sheds hereinbefore described require no description, since they need not differ from the usual warp-shed means with which an ordinary loom is equipped.

I do not herein claim the fabrics that the loom herein described is adapted to weave, nor do I claim the process of making the fabrics which the operation of the loom as herein described is adapted to practice; the structure of the fabrics 25 and the process of producing them forming the subject matter of other applications filed April 21, 1942, Serial No. 439,831 and 439,832.

What I claim and desire to protect by Letters Patent is:

1. A loom adapted to simultaneously weave two pile fabrics at different levels, comprising means to supply separate binder warp threads for each fabric and common pile warp threads, for both fabrics, two weft yarn supplies, one at each side of the loom, two shuttles, each adapted to engage a weft yarn from the supply at each side of the loom and pull a double pick thereof across the loom and then release the yarn, means to simultaneously throw both shuttles across the loom, one through sheds formed by the warp yarns of one fabric at one level and the other through the warp yarns of the other fabric at another level, and a cutter, located between the two woven fabrics as they are fed forward, adapted to sever the pile warp threads connecting and common to the two fabrics to thereby produce two separate pile fabrics.

2. A loom adapted to simultaneously weave two pile fabrics at different levels, means to supply 50 separate binder warp threads for each fabric and common pile warp threads for both fabrics, two weft yarn supplies, one at each side of the loom, two shuttles, each adapted to engage a weft yarn from the supply at each side of the loom and pull a double pick thereof across the loom and then release the yarn, means to simultaneously throw both shuttles across the loom, one through sheds formed by the warp yarns of one fabric at one level and the other through the warp yarns of the other fabric at another level, and means adapted, at the conclusion of each such two-shuttle throw, to move the shuttle that has traveled at the lower level to the higher level and move the shuttle that has traveled at the higher level to the lower level, whereby each shuttle acts, in its travel in opposite directions, to supply different weft yarns to both fabrics alternately.

3. In a loom, the combination with weft yarn supplies, one at each side of the loom, of two shuttles each adapted to engage a weft yarn from the supply at each side of the loom and pull a double pick thereof across the loom and then release the yarn, and means to throw both shuttles 70

simultaneously across the loom at different levels in opposite directions, a stationary shuttle box at each side of the loom, a shuttle lifter in one shuttle box adapted to be engaged by the shuttle that has traveled across the loom at a lower level, a shuttle depressor in the other shuttle box adapted to be engaged by the shuttle that has traveled across the loom at a higher level, means adapted, at the conclusion of each such two-shuttle throw, to raise said lifter and lower said depressor in their respective shuttle boxes to thereby respectively lift and lower the shuttles respectively engaged therewith preparatory to their next throw.

4. In a loom, the combination with weft yarn supplies, one at each side of the loom, of two shuttles each adapted to engage a weft yarn at one side of the loom and pull a double pick thereof across the loom, means to throw both shuttles 15 simultaneously across the loom at different levels in opposite directions, a shuttle lifter at one side of the loom adapted to be engaged by the shuttle that has traveled across the loom at a lower level, a shuttle depressor at the other side of the loom adapted to be engaged by the shuttle that has traveled across the loom at a higher level, a spring-actuated lever adapted to normally hold the lifter at the lower level, a spring-actuated lever adapted to normally hold the depressor at the upper level, and means, operable 20 at the completion of the throws of the shuttles, adapted to raise the lifter and lower the depressor and thereby reverse the levels of the shuttles preparatory to their next throw of the shuttles.

5. In a loom, the combination with two weft yarn supplies, one at each side of the loom, of two weft yarn shuttles each adapted to engage a weft yarn at one side of the loom and pull a double pick thereof across the loom, means to simultaneously throw the weft shuttles across the loom at different levels in opposite directions, two selvedge yarn shuttles, one at each side of the loom, movable through the loop of the double pick of weft pulled across the loom as aforesaid and means controlled by the weft shuttles to so actuate said selvedge shuttles.

6. In a loom, the combination with two weft 45 yarn supplies, one at each side of the loom, of two weft yarn shuttles each adapted to engage a weft yarn at one side of the loom and pull a double pick thereof across the loom, means to simultaneously throw both weft shuttles across the loom at different levels in opposite directions, two selvedge yarn shuttles, one at each side of the loom, movable through the loop of the double pick of weft pulled across the loom as aforesaid, means to so actuate said selvedge 50 shuttles, locking mechanism holding the selvedge shuttles from so actuating, and means actuated by the weft shuttle adapted to release said locking mechanism.

7. In a loom, the combination with two weft 55 yarn supplies, one at each side of the loom, of two weft yarn shuttles each adapted to engage a weft yarn at one side of the loom and pull a double pick thereof across the loom, means to simultaneously throw both weft shuttles across the loom at different levels in opposite directions, two selvedge yarn shuttles, one at each side of the loom, movable through the loop of the double pick of weft pulled across the loom as aforesaid, spring-actuated means to so actuate 60 said selvedge shuttles, locking mechanism holding said selvedge shuttles from being so operated,

and means actuated by the weft shuttles adapted to release said locking mechanism.

8. In a loom, the combination with two weft yarn supplies, one at each side of the loom, of two weft yarn shuttles each adapted to engage a weft yarn at one side of the loom and pull a double pick thereof across the loom, means to simultaneously throw both weft shuttles across the loom at different levels in opposite directions, two selvedge yarn shuttles, one at each side of the loom, movable through the loop of the double pick of weft pulled across the loom as aforesaid, a race along which each selvedge shuttle moves when so actuated, a plate carrying the selvedge shuttle and movable along the race, means to so move said plate and thereby so actuate said selvedge shuttle, means locking the plate to the selvedge shuttle race, and means actuated by the weft shuttle to release said plate-locking means.

9. In a loom, the combination with two weft yarn supplies, one at each side of the loom, of two weft yarn shuttles each adapted to engage a weft yarn from the supply at each side of the loom and pull a double pick thereof across the loom and then release the yarn, means to simultaneously throw both weft shuttles across the loom at different levels in opposite directions, means adapted, at the conclusion of each such two-shuttle throw, to move the shuttle at the higher level to the lower level and move the shuttle at the lower level to the higher level, whereby each shuttle moves first at one level in one direction to insert the yarn from one weft supply and then at the other level in the opposite direction to insert the yarn from the other weft supply, two selvedge yarn shuttles, one at each side of the loom, movable through the loops of the double picks of weft pulled across the loom as aforesaid, and means to so actuate said selvedge shuttles.

10. In a loom, the combination with the lay and shuttle boxes carried thereby at opposite sides of the loom, of two weft yarn supplies, one at each side of the loom, two weft yarn shuttles, means to simultaneously throw said weft shuttles across the loom in opposite directions into the respective shuttle boxes, means carried by the shuttles adapted to engage weft yarns on opposite sides of the loom and thereby in said throws pull two double picks of yarn across the loom, two selvedge yarn shuttles at opposite sides of the loom, each movable through the loop of the double pick of weft pulled across the loom as aforesaid, troughs, one at each side of the loom, movable with the lay and along which each selvedge shuttle moves, a plate carrying each selvedge shuttle and movable longitudinally of the trough, means to so move said plate and thereby so actuate said selvedge shuttle, means locking the plate to the trough, and means actuated by the weft shuttle to release said plate-locking means.

11. In a loom, the combination with the lay and shuttle boxes carried thereby at opposite sides of the loom, of two weft yarn supplies, one at each side of the loom, two weft yarn shuttles, means to simultaneously throw said weft shuttles across the loom in opposite directions into the respective shuttle boxes, means carried by the shuttles adapted to engage weft yarns on opposite sides of the loom and thereby in said throws pull two double picks of yarn across the loom, two selvedge yarn shuttles at opposite sides of the loom, each movable through the loop of the

double pick of weft pulled across the loom as aforesaid, troughs, one at each side of the loom, movable with the lay and along which each selvedge shuttle moves, a plate carrying each selvedge shuttle and movable longitudinally of the trough, spring-actuated means adapted to so move said plate and thereby so actuate the selvedge shuttle, means locking the plate to the trough, mechanism controlled by the lay to impose tension on said spring while the plate is locked to the trough, and means actuated by the weft shuttle to release said plate-locking means and thereby allow said spring-actuated means to so move said plate.

12. In a loom, the combination with the lay and shuttle boxes carried thereby at opposite sides of the loom, of two weft yarn supplies, one at each side of the loom, two weft yarn shuttles, means to simultaneously throw said weft shuttles across the loom in opposite directions into the respective shuttle boxes, means carried by the shuttles adapted to engage weft yarns on opposite sides of the loom and thereby in said throws pull two double picks of yarn across the loom, two selvedge yarn shuttles at opposite sides of the loom, each movable through the loop of the double pick of weft pulled across the loom as aforesaid, troughs, one at each side of the loom, movable with the lay and along which each selvedge shuttle moves, each trough being cut away in the line of travel of the weft carrier to allow a weft carrier to pass therethrough, a plate carrying said selvedge shuttle and movable longitudinally of the trough to thereby carry the selvedge shuttle across said line of travel of the weft carrier, means to so move said plate, means locking the plate to the trough, and means actuated by a weft shuttle, as it passes through said cut-away part of the trough, to release said plate-locking means.

13. In a loom adapted to simultaneously weave at different levels two fabrics containing separate wefts, the combination with a weft yarn supply at one side of the loom for the upper fabric and a weft yarn supply at the other side of the loom for the lower fabric, of two shuttles each adapted in its throw in one direction to engage the weft yarn from one supply, pull a double pick thereof across the loom at one level and then release the yarn and in its throw in the opposite direction to engage the weft yarn from the other yarn supply, pull a double pick thereof across the loom at the other level and then release the yarn, and means to throw the shuttles simultaneously across the loom at different levels in opposite directions.

14. In a loom, the combination with weft yarn supplies, one at each side of the loom, of two shuttles, means to throw both shuttles simultaneously across the loom at different levels in opposite directions, means adapted, at the conclusion of each two-shuttle throw, to move the shuttle at the higher level to the lower level and move the shuttle at the lower level to the higher level, a weft-yarn engaging device carried by each shuttle and adapted to engage yarn from one weft supply and pull a double pick thereof across the loom in one direction and alternately therewith to engage yarn from the other weft supply and pull a double pick thereof across the loom in the other direction, and means operable at the end of the throw of each shuttle to disengage said weft-yarn engaging device from the yarn which it has pulled across the loom.

15. In a loom adapted to simultaneously weave

at different levels two fabrics containing separate wefts, the combination with a weft yarn supply at one side of the loom for the upper fabric and a weft yarn supply at the other side of the loom for the lower fabric, of two shuttles, means to simultaneously throw both shuttles across the loom at different levels in opposite directions, means adapted, at the conclusion of each two-shuttle throw, to move the shuttle at the higher level to the lower level and move the shuttle at the lower level to the higher level, a weft-yarn engaging device carried by each

shuttle which before and after its throw across the loom at one level respectively engages and releases the yarn from one yarn supply and which before and after its throw across the loom at the other level respectively engages and releases the yarn from the other yarn supply, each shuttle thereby in opposite throws pulling a double pick of yarn from the two different supplies and thereby cooperating with the other 10 shuttle to form two fabrics with separate weft threads.

JOSEPH L. BAKER.
